IDLE AIR BYPASS MEANS

James T. W. Moseley, Glendale, Calif., assignor to Holley Carburetor Company, Warren, Mich., a corporation of Michigan

Continuation of application Ser. No. 734,159, May 9, 1958. This application June 28, 1962, Ser. No. 205,322

2 Claims. (Cl. 261—39)

This application is a continuation of my earlier application, Serial No. 734,159, filed on May 9, 1958, and now abandoned.

This invention relates generally to fuel systems for internal combustion engines, and more specifically to the means for supplying the air which is consumed by the engine during all conditions of idle operation.

The usual carburetor of present design delivers the air to the engine intake manifold by means of a partially open throttle valve. This method of maintaining idle engine operation has proved to be unsatisfactory especially in those situations where the engine has not reached normal operating temperatures and the ambient temperature is low. When a carburetor of this type is idled in cold weather, the moisture content of the air drawn around the "cracked" throttle frequently condenses and freezes adjacent to and on the upper surface and edges of the throttle valve due to the cooling effect of the air flowing past the throttle. The ice which is so formed may clog the idle fuel ports and cause engine stalling.

Various designs have been proposed to eliminate this icing, such as artificial heating of the carburetor by electrical means and idle air bypass means which obtain the idle air from within the induction passage anterior to the throttle and discharge it posterior to the throttle valve. However, none of these proposed general solutions eliminated the problem. The artificial heating is a costly and unpredictable method and the present idle air bypass means do not actually deal with the problem they purport to.

It is well known that an engine must idle at a higher r.p.m. during cold engine operation in order to continue to be self-sustaining. This means that more air must be introduced during that period than at idle operation when the engine has reached normal operating temperatures. All prior idle air bypass systems were of the fixed orifice type; that is, the amount of air allowed was determined for a certain ambient temperature condition. Since the temperature selected would have to be indicative of summer driving and the ambient temperature once the engine reached normal operating temperatures, the amount of air introduced would have to be less than that required by cold engine runs with low ambient temperatures.

In order to circumvent this apparent inconsistency between the original problem and proposed solutions, temperature controlled fast idle cams had to be employed in order to supply the additional air for fast idle-cold engine operation. Since the fast idle cams are used to hold the throttle valve open a certain amount, it is obvious that the prior solutions did not overcome the problem because they are almost entirely ineffective during the precise range of engine operation that the icing problem is at its worst.

Accordingly, an object of this invention is to provide means which will supply sufficient amounts of idle air for all conditions of engine idle operation.

More specifically, the object is to automatically provide a greater amount of air during cold engine operation than at normal engine operating temperatures without opening the throttle valve.

Other objects and advantages will become apparent

When reference is made to the following specification and illustrations in which:

FIGURE 1 illustrates in perspective a carburetor embodying the invention;

5 FIGURE 2 is a side elevational view, with portions thereof broken away and in cross-section, taken in the direction of the arrows of FIGURE 1. FIGURE 2 also illustrates a portion of the carburetor air cleaner and the engine;

10 FIGURE 3 is a fragmentary cross-sectional view of the carburetor taken substantially on line 3—3 of FIGURE 2;

FIGURE 4 is an enlarged fragmentary cross-sectional view of certain details illustrated in FIGURE 2;

15 FIGURE 5 is a cross-sectional view taken on line 4—4 of FIGURE 4;

FIGURE 6 is an exploded view in perspective of some of the elements illustrated in FIGURE 2;

FIGURE 7 is a schematic illustration of a modification of the invention;

20 FIGURE 8 is a graph illustrating the characteristic performance curves of the modification;

FIGURE 9 is a schematic illustration of the preferred embodiment of the invention shown by FIGURE 2;

25 FIGURE 10 is graph illustrating the characteristic performance curves of the preferred embodiment of the invention;

FIGURE 11 is a chart of the data used in preparing the graphs of FIGURES 8 and 10.

Referring now in greater detail to the illustrations, 30 FIGURE 1 illustrates a carburetor 10 having a throttle body 12 above which is located an air intake passage 14 having a choke valve 16 therein. A choke shaft 18 is secured to the choke valve and has at one end thereof secured to it a lever 20 which is adapted to be rotated by a rod 22 which is pivotally secured at its other end to an arm 24.

35 A choke operating assembly generally indicated at 26 contains the usual coiled bimetallic thermostat 27, one end of which is adapted to rotate arm 24 in accordance with temperature and engine operating requirements.

40 FIGURE 2, a cross-sectional view taken on line 2—2 of FIGURE 1, shows the air cleaner 28 fixed to the carburetor 10 and substantially enclosing therein the air intake 14. The carburetor body 12 contains induction 45 passages 30 and 32 (FIGURES 2 and 3), each having a main fuel nozzle 34, a venturi 36, an idle fuel transfer port 38, idle fuel port 40 and a throttle valve 42 mounted on a shaft 44 which is common to both induction passages. Both the main nozzle and idle fuel port receive their fuel through suitable conduit from the chamber of fuel bowl 46.

45 The above described structure is so well known in the art that any one skilled in the art will readily recognize it.

50 A constantly open idle air bypass system is illustrated by a vertical conduit 48, one end 50 of which is open to the chamber 52 generally formed by the air cleaner 28. The other end of conduit 48 is in communication with a laterally extending conduit 54 and the flow of air therethrough is adapted to be controlled by an adjustable needle valve 56 and coacting metering seat 58. A second laterally extending conduit 60 which is perpendicular to conduit 54 and in communication therewith has at its opposite ends vertical conduits 62 and 64 which in turn communicate with the induction passages 30 and 32 posterior to the throttle valves 42 by means of ports 66 and 68.

55 In addition to the constantly open air bypass system described above, a second variable air bypass communicates with conduit 54 posterior to needle valve 56 and seat 58. 60 This variable bypass may be comprised of a vertically extending conduit 70 having a substantially concentric meter-
